UNITED STATES PATENT OFFICE.

WILLIAM W. VINCENT, OF KENOSHA, WISCONSIN, ASSIGNOR TO THE VINCENT-ALWARD COMPANY, OF KENOSHA, WISCONSIN, A CORPORATION OF WISCONSIN.

WIRE-FORMING MACHINE.

1,313,509.

Specification of Letters Patent. Patented Aug. 19, 1919.

Application filed September 7, 1918. Serial No. 252,999.

To all whom it may concern:

Be it known that I, WILLIAM W. VINCENT, a citizen of the United States, residing at Kenosha, in the county of Kenosha and State of Wisconsin, have invented certain new and useful Improvements in Wire-Forming Machines, of which the following is a specification.

My invention pertains to machines for crimping or forming wire elements or sections and concerns more particularly, but not exclusively, appliances of this general character for automatically producing corrugated or crimped wire members from a supply roll of wire with suitably-shaped sharpened ends adapted to be driven into the framework of a piece of furniture and support the upright spiral-springs, such for example, as are employed in the seats of chairs, couches, and the like.

One object of the invention is the production of a machine of this character capable of adjustment whereby the lengths of the severed blanks may be regulated or changed and variations permitted in the number of crimps or bends in each wire section. These corrugations in the preferred embodiment of the invention are produced in wire blanks by intermeshing toothed wheels provided with automatically-acting means to cause them to mesh and separate or become temporarily inactive or inoperative, whereby, uncrimped ends may be provided in the wires. These crimping wheels are controlled as to their movements by cam means capable of regulation or adjustment to vary or change the number of corrugations per blank. The appliance also has cutting and feeding means for cutting off the blanks from the supply roll of wire, and this is also susceptible of adjustment to modify the lengths of the blanks.

In connection with these instrumentalities, there is also a press with suitably-formed interchangeable dies for shaping the ends or terminal portions of the wires. All of these parts of the mechanism work in proper timed relation to produce the desired results automatically, rapidly, and efficiently.

A further aim of the invention is the provision of a machine of this type which comprises but relatively few parts, unlikely to

become injured or damaged in service, which can be manufactured with comparatively small cost, and which is simple in structure and easily adjusted, some of its parts being removable or interchangeable to produce wires of radically different characteristics as to size and shape.

In order that those skilled in this art may have a full understanding of the invention and may appreciate its advantages from structural and functional standpoints, I have illustrated in the accompanying drawings forming a part of this specification, and throughout the various views of which like reference characters refer to the same parts, a preferred and desirable embodiment of the invention.

In these drawings:

Figure 1 is a plan view of the machine; Fig. 2 is an end elevation of the same with certain parts omitted;

Fig. 3 is a front view of the appliance with certain elements shown in section;

Fig. 4 is a fragmentary elevation with some of the parts shown in dotted lines;

Fig. 5 is a transverse section through the appliance showing the conveyer or carrier for the wires and the press for shaping their ends;

Fig. 6 shows one of the wire elements before its ends have been shaped or formed; and

Fig. 7 shows the completed product of the machine.

The appliance comprises a suitable framework 20 for the support of the various component parts of the machine including a pair of grooved wire feed-rolls 21 and 22, the upper one 22 of which is mounted for a slight vertical movement toward and from the lower one, whereby to permit temporary cessation of the feed during the cutting off operation. The lower roll 21 is fixed on a shaft 23 revolvably supported in any approved manner and at its end opposite the feed-roll it has a spur-gear 24 in mesh with a similar gear 25 on the corresponding end portion of shaft 26 on which the upper roller is fixed.

The bearing or bearings 27 for this latter shaft are capable of vertical movement as specified for the purpose indicated, being guided by the walls of the supporting-frame

recess 28. One or more coil expansion springs 29 act upon the bearings of such upper shaft and its feed-roll, tending to raise them, the shaft and grooved roll, however, being ordinarily held down to its work of advancing the wire by suitable means to be described.

These feed-rolls, as well as the remainder of the mechanism, are driven by suitable instrumentalities comprising a shaft 30 revoluble in bearings 31, 31, and equipped with two pulleys 32 and 33 both loose on the shaft, pulley 32 being rigid with a pinion 51 also free to turn on the shaft and driving a gear 15 52 on the lower feed-roll shaft 23.

In register with the pair of grooved feed-rolls, and adapted to act on the wire advanced thereby, I provide a pair of coöperating, toothed, wire crimping or corrugating rollers 43 and 47 mounted respectively on shafts 42 and 46 connected together by intermeshing gears 44 and 45 (Fig. 4) driven from shaft 23 by the intermediate or idler gear 48 coacting with gear 24. As 20 25 with the upper wire feed-roll, the corresponding corrugating-roller 47 is mounted for vertical play, the bearings for its shaft 46 being vertically slidably and pressed upwardly by one or more expansion springs 30 86, but ordinarily held down to its work by mechanism to be set forth.

Shaft 42 at one end is provided with a readily-removable or interchangeable gear 41 meshing with an idler 35 mounted on a short 35 shaft 36 adjustable in a slot 38 of a sector 37 supported by and capable of angular adjustment on shaft 42, being maintained in adjusted position by a screw 40 taking into a threaded hole in the framework and 40 extended through a curved or arcuate slot 39 in the sector. The intermediate gear 35 drives the larger gear 31 fixed to shaft 30 and hence rotates the latter. The shaft 30 is equipped with two, duplex, adjustable 45 cams 53, 54, controlling and governing respectively the action of the feed-rolls and wire-severing or cut-off device, and the crimping or corrugating rollers. By means of this construction allowing substitution of 50 different sizes of gears 41 the ratio of the gearing may be readily modified to effect variation in the operation of the machine.

Cam 53 consists of two recessed or cam parts 55, 56, arranged side by side on the 55 shaft and adjustable angularly relatively to one another to modify the position and size of the combined cam recess, whereby the moment and period of non-activity of the wire feed-rolls and the action of the cutting 60 or severing device may be varied as circumstances dictate. The lower end of a suitably-guided, vertical slide-bar 57 (Fig. 2) carries an appropriate cam roller 58 of sufficient length to overlie and coöperate with 65 the two parts of the compound or duplex

cam, the top end of the bar being loosely pivoted at 59 to an end of a rock-arm 60 fixed to a rock-shaft 61 rotatably mounted in bearings 62, 62. A rod 63, secured in supports 64, 64, upstanding from arm 60, 70 operates a clutch 65 of well-known construction, not necessary here to detail, on a shaft 66 revoluble in suitable bearings, and rotated when the clutch is active by a pulley 67, the shaft carrying a crank-arm 68 associated with a cross-head 69 guided by uprights 70, 70, and carrying at its lower end a diagonally-arranged knife or cutter 71 for severing blanks from the continuous strip of supply wire by coacting with a stationary 80 shear-member 72. Whenever this normally-inoperative clutch is tripped to render it temporarily active, shaft 66 makes one complete revolution and automatically stops, the knife or cutter performing one complete 85 reciprocation and effecting the severing operation. It is necessary or desirable to stop the feed or advance of the wire supply during such cutting, and, accordingly, shaft 61 has an arm 73 rigid therewith provided with 90 an adjustable screw 74, equipped with a lock-nut 75, engaging a projection 76 carried by the sliding bearing or bearings 27 of the upper wire feed-roll. As long as roller 58 is riding on the high part of the duplex- 95 cam 53, the feed-rolls will be held down in operative engagement with the wire against the pressure or lifting action of spring or springs 29, tending to separate them, and during this period the cutter will be out of 100 action. When the depression or recess in the double-cam reaches the roller, the latter enters it, rocking arm 73, permitting an automatic, temporary separation of the feed-rolls, thus stopping the wire feed, during 105 which period of inaction the cutter severs the wire. Soon afterward, however, the elevated portion of the compound cam engages the roller, raising it, thus again establishing the wire advance, during which 110 condition the cutter does not act.

To control the operation of the crimping or corrugating rollers independently of the wire feeding and cutting, shaft 30 is fitted with the second, adjustable duplex-cam 54, 115 substantially like the cam 53. This cooperates with a roller 80 on a vertical slide-bar 81 connected at its top end to a rock-lever 82 loose on shaft 61 and fitted at its other laterally-extended end with adjustable screws 83, provided with lock-nuts 84, engaging projections or lugs 85 on the bearing members of shaft 46 of the upper crimping-roller. Thus, when the recessed part of the cam comes under the roller, the upper 120 crimping-roller by virtue of the action of spring or springs 86 rises sufficiently to stop the crimping or corrugating operation, such crimping roller descending to operative 125 position again as soon as the cam turns 130

sufficiently to bring its elevated portion beneath the cam-roller.

The machine is also equipped with means to receive these corrugated wire-sections and 5 transport them laterally or transversely out of the path of travel of the oncoming wire to a suitable press for shaping or forming their uncrimped ends whereby the complete product will appear and have the form as 10 shown in Fig. 7. Any suitable style or character of mechanism may be employed for this purpose and that illustrated and described below is to be taken merely as an example of one way in which this work may 15 be readily accomplished.

On two parallel shafts 90 and 91 mounted in suitable bearings for rotation, there are pairs of sprocket-wheels 92 and 93 coating in the usual manner with a pair of parallel 20 sprocket-chains 94 disposed crosswise the direction of feed of the supply wire and beyond the cut-off knife. These chains carry a plurality of parallel, spaced, grooved, 25 cradles or supports 95, each adapted to receive one of the crimped wire members as it is sent forward and to hold it against tilting during its transportation to the press, the entrance end of each of such cradles being flared at 96 to facilitate the reception of 30 the crimped wire. These cradles or carriers are of less length than the wire sections and receive only their corrugated middle portions, leaving their uncrimped or straight 35 end sections projecting therefrom at both ends. Such cradles and their wires are stepped along intermittently, and in its travel each wire is ultimately brought into the press 97 whose properly-shaped die or 40 press blocks 98 and 99 are brought together by the usual mechanical means, thus deforming or shaping both ends of the wire simultaneously. This operation, of course, occurs during the periods of rest of the conveyer, the press acting successively on the 45 various wires as will be readily understood. The details of construction of this press it has been deemed unnecessary to present, it being only required to employ any suitable operating means acting in proper timed relation to other parts of the mechanism. The 50 die blocks are removable or interchangeable so that desired wire products of different shapes may be readily produced. After passing through the press, as the cradles 55 travel downwardly around the sprocket-wheels, the wire members are automatically dropped from the machine.

To effect the required step by step action of the conveyer or carrier, shaft 90 by intermeshing bevel-gears 100 and 101 is operatively associated with the jack-shaft 102 actuated intermittently by a cam 103 on 60 shaft 30 reciprocating a bar 104 by means of a cam-roller 105 traveling in the groove of 65 the cam, the bar rocking an arm 106 loose on

shaft 102 and equipped with a pawl 107 cooperating with a ratchet-wheel 108 fixed on shaft 102.

The mode of operation of the appliance takes place practically as follows:

The continuous wire supply is fed forwardly by and between the grooved feed-rolls, during which period the advance portion of the wire is crimped or corrugated by the registering interfitting toothed rollers, both the feed-rolls and the corrugating rollers being power-driven. These crimping rollers, of course, come into action and terminate their corrugating functions at the proper time by reason of their cam controlled approach toward and separation from one another. At the proper moment the feed-rolls separate, thus stopping the wire feed, the clutch becomes momentarily operative and causes the severance of the advanced crimped length of wire which now resides in one of the cradles or supports of the conveyer. The latter immediately carries the severed wire transversely out of the way, the feed of the supply wire is resumed, 80 and the cycle of operations repeated indefinitely. When the severed wire, in its intermittent travel, reaches the press, and during an interval of rest, this portion of the mechanism acts to shape its ends. When 85 the now completely shaped wire passes over the return bend of the endless conveyer it falls out of its cradle, thus being delivered or discharged from the machine.

One feature of importance of this machine 100 is its capability of adjustment for the production of wires of different lengths and with variable numbers of crimps or corrugations, the press also having the capacity for shaping ends into different forms, as 105 may be required. As will be readily understood, the wire feed and the amount or extent of crimping is controlled by the adjustable duplex-cams governing these functions. Also the operation of the machine may be 110 modified by substituting for the gear 41 one of a different number of teeth, the number of such teeth being that required in each instance to provide each wire section with the desired number of complete corrugations. When thus interchanging such gears it may be necessary to substitute a different size idler 35 but this is easily accomplished by reason of the feature of the adjustable support for such intermediate gear. In the 115 device as shown, the press would require different or adjustable die blocks for wires of different lengths and shapes, but obviously, this substitution could be made readily and without difficulty.

Whereas in this application I have presented one desirable embodiment of the invention, it is to be understood that the latter is susceptible of a variety of embodiments and that many minor mechanical 120 125 130

changes may be made in the structure set forth without departure from the heart and essence of the invention and without the sacrifice of any of its substantial benefits 5 and advantages.

I claim:

1. In a wire-forming machine of the character described, the combination of means to feed a wire supply, means to sever said supply into lengths, means to crimp the wire comprising a pair of corrugated rollers between which the wire passes, and automatically-acting means to cause said rollers to approach one another and to separate to render them operative and inoperative on the wire, substantially as described.
2. In a wire-forming machine of the character described, the combination of means to crimp the wire comprising a pair of corrugated rollers between which the wire passes, and adjustable automatically-acting means to cause said rollers to approach one another and to separate to render them operative and inoperative on the wire, substantially as described.
3. In a wire-forming machine of the character described, the combination of means to feed a wire supply, means to sever said supply into lengths, means to crimp the wire comprising a pair of corrugated rollers between which the wire passes, and adjustable cam means controlling the approach of said rollers toward one another and their separation to render them operative and inoperative on the wire, thus permitting variations in the number of crimps put in each section of the wire, substantially as described.
4. In a wire-forming machine of the character described, the combination of means to feed a wire-supply, means to sever said supply into lengths, means to crimp the wire comprising a pair of corrugated rollers between which the wire passes, spring 45 means tending to separate said rollers, and adjustable cam means controlling the relative positions of said rollers rendering them operative and inoperative on the wire, thus permitting variation in the number of crimps put in each section of the wire, substantially as described.
5. In a wire-forming machine of the character described, the combination of power-driven feed-rollers to advance a wire-supply, means to sever said supply into lengths, means to crimp the wire comprising a pair of power-driven corrugated rollers between which the wire passes, and adjustable means controlling the approach of said rollers to 60 ward one another and their separation to render them operative and inoperative on the wire, thus permitting variations of the number of crimps put in each section of the wire, substantially as described.
6. In a wire-forming machine of the character described, the combination of inter-

mittently-operative power-driven feed-rollers adapted to advance a wire-supply, adjustable means to vary the period of action of said rollers, means to sever said wire supply into lengths during the periods of inaction of said feed-rollers, a pair of corrugated rollers to crimp the wire passing between them, and means to render said rollers operative and inoperative upon said wire, whereby to vary the number of crimps put in each section of the wire, substantially as described.

7. In a wire-forming machine of the character described, the combination of means to feed a wire supply, means to sever said supply into sections diagonally to provide sharp ends, means to adjust the action of said feeding means to modify the lengths of the severed sections, means to crimp the wire comprising a pair of corrugated rollers between which the wire passes, adjustable means to cause said rollers to approach one another and to separate to render them operative and inoperative on the wire, thus permitting variations in the number of crimps put in each section of the wire, means to intermittently feed the severed wire sections transversely to their lengths and prevent them from tilting, and means to bend 95 to shape the uncrimped end portions of such laterally-moved wire sections while the latter are stationary, substantially as described.

8. In a wire-forming machine of the character described, the combination of means to feed a wire-supply, means to sever said supply into lengths, means to crimp the wire comprising a pair of corrugated rollers between which the wire passes, automatically-acting means to cause said rollers to approach one another and to separate to render them operative and inoperative on the wire, gearing controlling the action of said automatically-acting means, and means permitting a change of gear ratio of said gearing 110 to modify the action of said crimping means, substantially as described.

9. In a wire-forming machine of the character described, the combination of means to feed a wire-supply, means to sever said supply into lengths, means to crimp the wire comprising a pair of corrugated rollers between which the wire passes, adjustable automatically-acting means to cause said rollers to approach one another and to separate to render them operative and inoperative on the wire, gearing controlling the action of said adjustable means, and means permitting a change of gear ratio of said gearing 120 to modify the action of said crimping means, substantially as described.

10. In a wire-forming machine of the character described, the combination of means to feed a wire-supply, means to sever said supply into lengths, means to crimp 130

the wire comprising a pair of corrugated rollers between which the wire passes, adjustable automatically-acting cam means to cause said rollers to approach one another 5 and to separate to render them operative and inoperative on the wire thus permitting variations in the number of crimps put in each section of the wire, gearing controlling the action of said adjustable cam means, and 10 means permitting a change of gear ratio of said gearing to modify the action of said crimping means, substantially as described.

11. In a wire-forming machine of the character described, the combination of 15 means to feed a wire-supply, means to sever said supply into lengths, means controlling the action of said wire-feeding means, means to crimp the wire comprising a pair of corrugated rollers between which the wire 20 passes, automatically-acting means to cause said rollers to approach one another and to separate to render them operative and inoperative on the wire, gearing governing the action of said controlling means and said 25 roller operating means, and means permitting a change of gear ratio of said gearing, substantially as described.

12. In a wire-forming machine of the character described, the combination of 30 means to feed a wire-supply, means to sever said supply into lengths, adjustable automatically-acting means controlling the action of said wire feeding means, means to crimp the wire comprising a pair of corrugated rollers between which the wire passes, adjustable automatically-acting means to cause said rollers to approach one another and to separate to render them operative and inoperative on the wire, gearing controlling the action 35 of both of said adjustable means,

and means permitting a change of gear ratio of said gearing, substantially as described.

13. In a wire-forming machine of the character described, the combination of 45 means to feed a wire-supply, means to sever said supply into lengths, adjustable means governing the action of said severing means, adjustable means governing the action of said feeding means, means to crimp the wire comprising a pair of corrugated rollers be- 50 tween which the wire passes, adjustable means governing the action of said corrugated rollers on said wire by causing said rollers to approach one another and to separate thus permitting variations in the number of crimps put in each section of the 55 wire, gearing controlling the action of said three adjustable means, and means permitting a change of gear ratio of said gearing, substantially as described. 60

14. In a wire-forming machine of the character described, the combination of means to feed a wire-supply, means to sever said supply into lengths, adjustable automatically-acting cam means governing the 65 action of said feeding means and said severing means, means to crimp the wire comprising a pair of corrugated rollers between which the wire passes, adjustable automatically-acting cam means governing the action 70 of said rollers on said wire by causing said rollers to approach one another and to separate to render them operative and inoperative on the wire thus permitting variations in the number of crimps put in each section 75 of the wire, gearing controlling the action of said two adjustable cam means, and means permitting a change of gear ratio of said gearing, substantially as described.

WILLIAM W. VINCENT.
